UNITED STATES PATENT OFFICE.

HENRY SPENCER BLACKMORE, OF MOUNT VERNON, NEW YORK.

ELECTROLYTIC APPARATUS.

SPECIFICATION forming part of Letters Patent No. 759,798, dated May 10, 1904.

Application filed July 22, 1903. Serial No. 166,567. (No model.)

To all whom it may concern.

Be it known that I, HENRY SPENCER BLACKMORE, a citizen of the United States, residing at Mount Vernon, in the county of Westchester 5 and State of New York, have invented new and useful Improvements in Electrolytic Apparatus, of which the following is a specification.

This apparatus is especially intended for the electrolysis of an aqueous solution of sodium 10 chlorid upon a mercury cathode and the removal of the sodium from the resulting amalgam as sodium hydrate, being fully described in pending United States application, Serial No. 85,099, filed December 7, 1901.

15 Referring to the accompanying drawings, Figure 1 is a longitudinal vertical section of the apparatus, taken on line I I of Fig. 2. Fig. 2 is a plan view, partly in horizontal section; and Fig. 3 illustrates a modification using a siphon 25' to draw off the alloy from the electrolytic cell, a body of liquid other than the electrolyte being used in the intermediate vessel 28—for example, carbon bisulfid, carbon tetrachlorid, &c.

25 The apparatus consists of the following parts:

A vessel 1 communicates by bottom outlet 2 with a chamber 3. Within chamber 3 is a ball-float 4, communicating by rod 5, lever 6, 30 and link 7 with a valve 8 in outlet 2. This float feed mechanism serves to maintain a column of mercury at uniform level in chamber 3. An outlet-pipe 9, leading from the bottom of chamber 3, opens into a manifold 10, which 35 in turn has several lateral outlet-pipes 11, opening into the bottom of electrolytic cell 12. The layer of mercury 13 thus introduced upon the bottom of electrolytic cell is connected to act as cathode. Supported upon 40 the cathode 13 is a body of an aqueous solution of sodium chlorid or other electrolyte 14. The cover 15 of the electrolytic cell has a number of openings 16, arranged in parallel rows. Above each row of openings is a strip 17 of 45 insulating material, which serves to support the stems 18 of anodes 19. The cover 15 has also a number of vertical outlet-pipes 20 for chlorin leading into a manifold. Upon each end of the electrolytic cell is arranged a 50 receptacle 22 for solid sodium chlorid or other

electrolyte. These receptacles are in open communication with the electrolyte in cell 13 by openings 23 and serve to maintain it in a saturated condition. From the side of cell 13 one or more sets of pipes 24 25 lead into one 55 or more vessels 26, from the bottom of which in turn a valve-pipe 27 leads into the oxidizing vessel 28. Pipe 24 serves to put the electrolyte into open communication with a similar body of liquid 29 in vessel 26, while pipe 60 25 is arranged to draw off the liquid amalgam produced by electrolysis as soon as the pipe rises above the normal level of the cathode.

The oxidizing vessel 28 is divided into a number of parallel compartments alternately 65 communicating at opposite ends by vertical baffle-plates 35. The liquid amalgam is introduced by pipe 27 into one of the end compartments and flows back and forth through the succeeding compartments to an outlet-70 pipe 32. Adjacent to but above outlet 32 is an inlet-pipe 33 for water or other oxidizing agents. The introduced water flows over the surface of the amalgam and serves to remove therefrom the sodium or other easily-oxi-75 dizable metals, the resulting sodium hydrate escaping through the valved outlet-pipe 34. The rate of oxidation of the sodium may be increased by placing electrodes 35, of carbon or other relatively electronegative material, 80 in the water and putting them in electrical communication with the amalgam below, either directly or by connecting the amalgam with the positive lead of the electrolyzing-current and the carbon electrodes with the negative lead, 85 thereby utilizing the electrical energy generated in the oxidizing-cell to furnish current to the electrolyzing-cell. Pipe 32 serves to carry the depleted alloy metal from the oxidizing-cell into an adjoining vertical cylinder 90 36, in the bottom of which is a valve-outlet 37, controlled by a float 38. A pipe 39 leads from outlet 37 into a receiving vessel 40. The mercury collected in vessel 40 is returned by pipes 41, including pump 42 or otherwise, to 95 the reservoir 1. The movement of mercury and amalgam through the various vessels is effected solely by the differences of level of the various bodies of mercury and amalgam, and these differences are maintained by suit-100

able predetermined adjustment of float-feed 8 and float-controlled outlet 37 and of the height of the connecting-pipes. The connecting-pipes between the various vessels are preferably of hard rubber or vitrified earthenware to insulate the vessels from each other. The pipe 21 for removing chlorin is preferably connected with an exhaust device to maintain a slight vacuum over the electrolyte 10 and facilitate the escape of chlorin. The maintenance of the electrolyte in a saturated condition tends to prevent the absorption of chlorin by it and prevents the charges of level which would otherwise occur. The outlet-pipe 34 for sodium hydrate should be somewhat larger than the water-inlet pipe 33 and serves to maintain a constant level of the water in the oxidizing-chambers.

By the use of vessels which are provided 20 with heating means the apparatus may be adapted for the electrolysis of molten sodium chlorid upon a cathode of molten metal, such as lead, any suitable means being employed for oxidizing and removing the sodium, such 25 as a stream of molten sodium hydrate flowing in contact with the lead-sodium alloy or injected into the body of the alloy, the resulting sodium oxid being regenerated, if desired, by the action of steam.

30 The term "alloy" as used in the claims is intended to cover a solution of an oxidizable metal in any alloying metal, whether mercury or lead.

As is well known, the addition of a comparatively small amount of an alkali or an alkaline-earth metal to mercury converts the latter into a pasty condition in which it does not readily flow. This difficulty may be avoided when mercury is employed as a cathode by 35 applying heat to it, thereby maintaining the amalgam produced by electrolysis in fluent condition and enabling larger percentages of sodium to be absorbed without interfering with the continuous overflow of amalgam into 40 the oxidizing vessel. Such heat may be supplied by a gas-burner 44 beneath the electrolytic cell, as indicated by dotted lines in Fig. 1.

I claim

1. An electrolytic apparatus comprising an electrolytic cell having an anode, a liquid-metal cathode, an outlet near the upper surface of the cathode and a body of electrolyte supported by the cathode, and a feed device for supplying additional liquid metal to the cathode as the alloy produced by electrolysis flows off through said outlet, means whereby the feed device controlled by variations in the density of the cathode, as set forth.

2. An electrolytic apparatus comprising an electrolytic cell having an anode, a liquid-metal cathode, an outlet near the upper surface of the cathode, a body of electrolyte supported by the cathode, a saturator for maintaining the body of the electrolyte at uniform density, 65 and a feed device for supplying additional

liquid metal to the cathode as the alloy produced by electrolysis flows off through said outlet, means whereby the feed device controlled by variations in the density of the cathode as set forth.

3. An electrolytic apparatus comprising an electrolytic cell having an anode, a liquid-metal cathode, an outlet near the upper surface of the cathode, and a body of electrolyte supported by said cathode, an adjoining chamber 75 containing a column of the liquid metal, said column in communication with the cathode and balanced by the weight of the cathode and superposed electrolyte, and means for supplying additional liquid metal to said column controlled by the variations in density of the cathode and maintaining its level substantially uniform, as portions flow into the electrolytic cell, as set forth.

4. An electrolytic apparatus comprising an electrolytic cell having an anode, a liquid-metal cathode, an outlet near the upper surface of the cathode, and a body of electrolyte supported by said cathode, an adjoining chamber containing a column of the liquid metal, said column in communication with the cathode and balanced by the weight of the cathode and superposed electrolyte, a reservoir of the liquid metal and an inlet from said reservoir to said chamber, having a float-feed controlled 95 by the height of the column in said chamber, as set forth.

5. An apparatus for oxidizing and removing metals from their liquid alloys comprising an oxidizing vessel containing a layer of the alloy, an oxidizing agent supported by said layer, an outlet device for the alloying metal controlled by the height of said layer, and a reservoir of the alloy communicating with the oxidizing vessel and arranged to automatically 100 supply a fresh alloy as the depleted alloying metal flows from the oxidizing vessel, as set forth.

6. An apparatus for oxidizing and removing metals from their liquid alloy, comprising an oxidizing vessel containing a layer of the alloy, an oxidizing agent supported by said layer, an outlet for the alloying metal having a float-valve controlled by the height of said layer, and a reservoir of the alloy communicating with the oxidizing vessel and arranged to supply fresh alloy as the depleted alloying metal flows from the oxidizing vessel, as set forth.

7. An apparatus for oxidizing and removing metals from their liquid alloys, comprising a vessel having tortuous passage, an inlet for the alloy at one end of the passage, an outlet for the alloying metal at the other end of the passage, an inlet for a liquid oxidizing agent 120 adjacent to but above the said outlet, and an outlet for the product of oxidation adjacent to the said inlet for alloy and arranged to maintain a uniform layer of the oxidizing agent 125 above the alloy, as set forth.

8. An electrolytic apparatus comprising an electrolytic cell having liquid-metal cathode, an oxidizing vessel, an independent body of electrolyte between said cell and vessel, and 5 passages arranged to carry the alloy produced by electrolysis through said independent body of electrolyte and into the oxidizing vessel, thereby preventing short-circuit between the cathode and the alloy in the oxidizing vessel, 10 as set forth.
9. An electrolytic apparatus comprising an electrolytic cell having an anode, a liquid-metal cathode, and a body of electrolyte supported by the cathode, an oxidizing vessel containing 15 a layer of liquid alloy produced by electrolysis, and an intermediate chamber having separate passages communicating with said electrolyte, cathode, and layer of alloy, as set forth.
10. An electrolytic apparatus comprising a reservoir of liquid metal, an electrolytic cell communicating with said reservoir and having a layer of said liquid metal as cathode and a body of electrolyte supported by said cathode, 20
- 25 an outlet near the surface of said cathode leading to an oxidizing vessel, a layer of the liquid alloy produced by electrolysis in said oxidizing vessel and supporting an oxidizing agent, an outlet arranged to lead the depleted alloying metal into an adjoining chamber, said chamber and an outlet from the bottom of

said chamber controlled by the height of the alloying metal in said chamber, the bodies of metal, electrolyte, alloy, and oxidizing agent in the reservoir, electrolytic cell, oxidizing 35 vessel and said chamber, being normally balanced, whereby electrodeposition of a light metal upon the cathode causes the resulting alloy to overflow into the oxidizing vessel, the depleted alloying metal to flow from the oxidizing vessel into said chamber and a further quantity of the alloying metal to flow from the reservoir into the electrolytic cell, as set forth.

11. An electrolytic apparatus, comprising an electrolytic cell having an anode, a liquid-metal cathode, an outlet near the upper surface of the cathode, and a chamber containing a body of liquid which is inert toward the alloy produced in the electrolytic cell, said chamber communicating with the outlet of said cell, whereby said inert liquid serves to counterbalance the weight of the electrolyte while permitting free outflow of the alloy produced by electrolysis, as set forth.

In testimony whereof I have signed my name 55 to this specification in the presence of two subscribing witnesses.

HENRY SPENCER BLACKMORE.
